UNITED STATES PATENT OFFICE.

HARRY J. HENDRICKS, OF STERLING STATION, NEW YORK.

LUBRICATING SYSTEM.

1,391,634.

Specification of Letters Patent. Patented Sept. 20, 1921.

Application filed November 15, 1920. Serial No. 424,164.

To all whom it may concern:

Be it known that I, HARRY J. HENDRICKS, a citizen of the United States, residing at Sterling Station, in the county of Cayuga and State of New York, have invented certain new and useful Improvements in Lubricating Systems, of which the following is a specification.

This invention relates to lubricating systems especially adapted for use on motor vehicles and has primarily for an object the provision of a system which automatically maintains the level of the lubricant in the engine base at a predetermined height.

Another object of the invention is to provide a simple and inexpensive device of this character which is especially adapted for use on Ford cars, although of course the device is applicable for use with any type of engine using the splash system of lubrication.

The above and other objects of this invention will be in part described and in part understood from the following description of the present preferred embodiment of the invention taken in connection with the accompanying drawings, wherein:

Figure 1, is a side elevational view of a system constructed in accordance with my invention illustrating its application.

Fig. 2, is a vertical sectional view thereof showing parts removed.

Fig. 3, is a detail fragmentary sectional view of the device showing especially the valve arrangement for the filler cap, and

Fig. 4, is a detail fragmentary sectional view showing especially the regulating pocket.

In the drawings in order to illustrate the application of this invention a portion of a motor vehicle body 5 is shown, the end of the floor of which is inclined upwardly as indicated at 6 and has upstanding from the front end thereof a dash board 7.

The device of this invention consists especially of an oil supply tank 8, the upper face of which is preferably beveled to snugly engage the inclined portion 6 of the floor of the vehicle and has upstanding

therefrom a supporting bar 9. The said bar is bolted or otherwise secured to the dash board 7. As is apparent the bar 9 is arranged on the top of the supply tank 8 and secured thereto in any desired manner.

The rear end of the tank has an apertured

extension 10 formed thereon through which the body bolt of the car may extend if desired. The tank 8 has a small reservoir 11 depending therefrom which is preferably of a cylindrical configuration and is provided with a lateral outlet opening 12 which carries an outlet conduit 13. The conduit 13 terminates in a regulating pocket 14, which latter is mounted in the base of an engine 15. The pocket 14 is preferably of a cylindrical configuration and terminates at its lower end in a cylindrical barrel 16, one end of the latter extending into the base of the engine 15. The oil is in this way conveyed from the tank 8 through the conduit 13, thence through the pocket 14 and into the barrel 16 from which it passes into the engine as shown to advantage in Fig. 4. The regulating pocket 14 is suitably vented as shown in Fig. 4 of the drawings, whereby when the oil reaches the lower end of the conduit 13 within the pocket 14, communication will be closed through the conduit forming a partial vacuum in the latter. As soon however as the level of the oil lowers in the engine so as to uncover the lower end of the conduit, air will be permitted to pass through said conduit, thereby relieving the vacuum and permitting the oil to pass from the supply tank into the regulating pocket until the lower end of the conduit is again sealed by the oil.

In order to determine at all times the exact amount of lubricant in the tank 8, a suitable sight 17 is provided, which in this instance consists of a transparent tube which is in communication with the top of the supply tank 8 and extends upwardly through the floor of the vehicle directly in front of the dash board 7 as shown in Fig. 1. This tube may, of course, be covered with a suitable non-frangible material. A float 18 is mounted in the supply tank and has a rod 19 upstanding therefrom and extended into the sight 17. Any suitable type of indicating finger, such as that indicated at 20, may be mounted upon the upper end of the rod which will be visualized through the sight 17.

In order that the vacuum will not be broken when the supply tank 8 is being replenished, a valve 21 is provided which is yieldingly mounted in the reservoir 11 and is adapted to automatically engage a valve seat in said reservoir as soon as the

filler cap 22 of the supply tank is removed. The spring which actuates the valve is sufficient to overcome the resistance of the liquid in the tank, thereby positively holding the 5 valve closed until the filler cap has been again screwed into the tank.

Various changes may be made in this device so as to adapt it for use on motor vehicles other than Ford cars, without departing from the spirit of this invention. 10 Moreover, various changes may be made by me in the details of construction, proportion and arrangement of parts without departing from the invention as covered in the 15 appended claim.

What is claimed is:

In combination with a vehicle engine having a conventional lubricating base, a sup-

ply tank, a lubricant conduit depending from said tank and into said vehicle engine 20 base, and a ventilating pocket including a cylindrical body one end of which passes through the wall of the engine base and is engaged with the lubricating conduit inside of the base, the opposite end of said cylindrical body issuing into a right angular cylindrical member outside of the base, one end of said right angular member extending 25 into said engine base.

In testimony whereof I affix my signature 30 in presence of two witnesses.

HARRY J. HENDRICKS.
